(57) **CLAIM**

The ornamental design for a utility belt holder for various size buckles, as shown and described.

DESCRIPTION

FIG. 1 is a view of the front of said utility belt holder with buckle suspension arms fully extended.

FIG. 2 is a top view of FIG. 1.

FIG. 3 is a front view of FIG. 1 with the buckle suspension arm embodiments fully retracted.

FIG. 4 is a top view of FIG. 3 with buckle suspension arm embodiments shown retracted.

FIG. 5 is an axonometric view of FIG. 1 from the front/left with buckle suspension arm embodiments fully extended. Said utility belt holder is shown in solid lines, broken line matter being for illustrative purposes only. Said utility belt holder is depicted in use suspended on a pole.

FIG. 6 is an axonometric view of FIG. 3 from the top/left of said utility belt holder with buckle suspension arm embodiments fully retracted. Said utility belt holder is shown in solid lines, broken line matter being for illustrative purposes only. Said utility belt holder is depicted in use suspended on a pole. FIG. 7 is an axonometric view of FIG. 3 from the right side thereof.

FIG. 8 is an axonometric view of FIG. 3 from the rear of said utility belt holder with buckle suspension arm embodiments fully retracted. Said utility belt holder is shown in solid lines, broken line matter being for illustrative purposes only. Said utility belt holder is depicted in use suspended on a pole.

FIG. 9 is an axonometric view of FIG. 1 from the rear of said utility belt holder with buckle suspension arm embodiments fully extended. Said utility belt holder is shown in solid lines, broken line matter being for illustrative purposes only. Said utility belt holder is depicted in use suspended on a pole.

FIG. 10 is an axonometric view of the front of FIG. 1 with dashed lines depicting hanging pole.

FIG. 11 is an axonometric view of the front of FIG. 3 with dashed lines depicting hanging pole.

FIG. 12 is an axonometric view of the rear of FIG. 1 of said utility belt holder with buckle suspension arm embodiments fully extended. Said utility belt holder is shown in solid lines, broken line matter being for illustrative purposes only. Said utility belt holder is depicted in use suspended on a pole; and,

FIG. 13 is an axonometric view of the rear of FIG. 3 of said utility belt holder with buckle suspension arm embodiments fully retracted. Said utility belt holder is shown in solid lines, broken line matter being for illustrative purposes only. Said utility belt holder is depicted in use suspended on a pole.

My utility belt holder is characterized by an embodiment which suspends the buckle of a utility belt in a safe and secure manner when said utility belt is not being worn.
